(57) **CLAIM**

The ornamental design for a flat profile frame with dentil shelf for glass insert on door, as shown and described.

DESCRIPTION

FIG. 1 is a front perspective view of a flat profile frame with dentil shelf for glass insert on door, as depicted in solid lines; FIG. 2 is a front elevation view thereof; FIG. 3 is a rear elevation view thereof; FIG. 4 is a side elevation view thereof; FIG. 5 is a side elevation view thereof, for the side opposite that of FIG. 4; FIG. 6 is a top elevation view thereof; FIG. 7 is a bottom elevation view thereof; FIG. 8 is a rear perspective view thereof; and, FIG. 9 is a front perspective environmental view thereof. The broken lines shown in the drawings are only provided to illustrate the environment of the design, and form no part of the claimed design.
